Patented Aug. 14, 1917.

UNITED STATES PATENT OFFICE.

CHARLES F. KOTEK, OF CHICAGO, ILLINOIS.

NETHERGARMENT.

1,236,720.

Specification of Letters Patent. Patented Aug. 14, 1917.

Application filed November 23, 1916. Serial No. 133,018.

To all whom it may concern:

Be it known that I, CHARLES F. KOTEK, a citizen of the United States, residing at Chicago, in the county of Cook and State of Illinois, have invented certain new and useful Improvements in Nethergarments, of which the following is a specification.

This invention relates to new and useful improvements in nether garments and more particularly to ladies' under-vests.

The object of my invention is to combine with an under-vest of the sleeveless type and having a low-neck opening, a pair of sleeves which may readily be attached to or detached from the shoulder straps of said vest, whereby said vest with the sleeves attached may be worn under a shirt-waist or dress designed for street or every day wear, and whereby it will be unnecessary for the wearer to remove the entire under-vest when changing said outer garment for an evening bodice of the sleeveless or transparent type, as the sleeves may be readily detached to thereby convert said under-vest to one of a character adapted for wear under an evening outer garment such as described.

In the accompanying drawing, which shows one embodiment of my invention,

Figure 1 is a front elevation of the under-vest showing one sleeve attached to, and the other sleeve detached from the shoulder straps.

Fig. 2 is an enlarged sectional view showing the connection between the upper end of a sleeve and the corresponding shoulder strap, and

Fig. 3 is an enlarged detail perspective view.

Referring to the drawing, I have shown a lady's under-vest of the sleeveless type and preferably formed of knitted material, which consists of a tubular body-encircling portion 5, the front and back upper edges thereof being scalloped to form a resultant low neck opening 6 and spaced shoulder straps 7-7 for supporting said body portion 5. While I have shown the under-vest as being a separate garment, it will be obvious that the same might be embodied in a union suit.

Combined with this under-vest are sleeves 8-8, which may be either of half length or full length. The upper ends of these sleeves and the shoulder straps of the under-vest

5 by said sleeves may be readily detached from the vest without the necessity of the wearer having to remove the body portion 5. To this end, the shoulder straps of the under-vest are respectively provided with spaced 60 openings 9-9, which may be either formed in the shoulder strap itself or by a cross bar edging being attached to said shoulder straps. The upper ends of the sleeves are each preferably formed with spaced openings 10-10 corresponding in number to the openings 9-9 above described, or these openings 10-10 may be formed by a cross bar edging being attached to the upper ends of said sleeves. Tapes 11-11 are laced 70 through the corresponding openings of the shoulder straps and the sleeves so as to detachably connect the upper ends of said sleeves with the respective shoulder straps of said under-vest.

From the foregoing, it will be readily apparent that I have provided a lady's under-vest with sleeves which are detachably connected to the shoulder straps of said under-vest, whereby said vest may be worn under 80 a shirtwaist or dress designed for street or every day wear. It will also be obvious that by means of my invention it will be unnecessary for the wearer to remove the body-encircling portion 5 when changing said outer 85 garment for an evening bodice of the sleeveless or transparent type, as the sleeves may be readily detached to thereby convert said under-vest to one of the character adapted for wear under an evening outer garment of 90 the character described.

What I claim is:

The combination with a lady's sleeveless under-vest, including a body-encircling portion having a low neck opening, and relatively narrow shoulder straps for supporting said body portion disposed at opposite sides of said neck opening, the outer edges of the shoulder straps being in substantial alignment with the side lines of the body 100 portion, of arm-sleeves, and means detachably connecting the upper ends of said sleeves directly with the respective shoulder straps.

In testimony whereof I affix my signature 105 in the presence of two witnesses.

CHARLES F. KOTEK.

Witnesses:

FRANK KASPAR,
JOHN HLIBAL.
